GREASE PUMP

William Harrigan, Rutherford, N. J.

Application September 20, 1952, Serial No. 310,664

2 Claims. (Cl. 222—227)

This invention relates in general to apparatus for supplying liquids or semi-liquids such as lubricating greases to the desired points of use under pressure. The apparatus includes a container, a delivery hose or pipe, a gear pump for forcing the substance being pumped from the container to said delivery hose, and a reciprocating pump for ejecting the grease into the delivery hose at relatively high pressure for transmission to the point of use.

It is desirable to have in such apparatus means for efficiently handling or pumping greases or other viscous substances that are different in consistency, viscosity, and thickness. Therefore, one object of the invention is to provide in apparatus of this character novel and improved means wherein the ratio of the gears of the gear pump may be easily and quickly changed for the purpose of handling different greases or other substances.

It is necessary to include in such apparatus means for relieving the delivery hose of the high pressure when the delivery nozzle is closed or some other obstruction to the flow of the grease through the hose is encountered; and it has been customary to provide a relief valve in one of the pump passages for permitting the grease to be bypassed into the container under the specified conditions. These arrangements of relief valves are sometimes complicated and expensive and often are not entirely satisfactory. Therefore, another object of the present invention is to provide a novel and improved construction and combination of a relief valve and the piston of the reciprocating pump, which shall be simple and inexpensive, reliable and durable, and shall permit easy and quick adjustment of the pressure generated by said piston on its power stroke.

Other objects, advantages, and results of the invention will be brought out by the following description in conjunction with the accompanying drawings in which

Figure 1 is a central vertical sectional view of a dispensing apparatus or pump constructed in accordance with the invention;

Figure 2 is a horizontal sectional view approximately on the plane of the line 2—2 of Figure 1;

Figure 3 is a transverse vertical sectional view approximately on the plane of the line 3—3 of Figure 1;

Figure 4 is an enlarged fragmentary vertical sectional view approximately on the plane of the line 4—4 of Figure 2 with parts omitted;

Figure 5 is an enlarged transverse vertical sectional view approximately on the plane of the line 5—5 of Figure 4; and

Figure 6 is a horizontal sectional view through a gear pump casing body detached from the apparatus and showing a gear ratio different from that illustrated in Figure 1.

Specifically describing the illustrated embodiment of the invention, the apparatus comprises a container or tank A for the substance to be dispensed or pumped.

Within the container A and supported on the bottom thereof is a pumping apparatus generally designated B which includes a frame having a base portion 2, a gear pump casing body 3 and a gear pump casing cover 4 which

2

has apertures 5 therein to permit the flow of grease downwardly around the pumping apparatus.

As shown, the gear pump casing body 3 includes a pump chamber 6 in which are journaled two gears 7 and 8, one of which is mounted on a vertical counter-drive shaft 9 which is driven by a worm gear 10 on the shaft 9 meshing with a worm 11 on a main drive shaft 12 which is connected to any suitable source of power, for example an electric motor C mounted outside of the container.

10 The pump chamber 6 has an outlet passage 13 and an inlet passage 14 which faces upwardly into the container A and has an upstanding flange 15 at one side thereof. The other pump gear 8 is mounted on a jack shaft 16 which is journaled in bearings 17 and 18 in the pump casing body and cover, respectively. The counter-drive shaft 9 is journaled in bearings 19 and 20 in the pump casing and the base portion 2 of the frame, respectively.

Above the pumping apparatus and keyed on the jack shaft 16 is a combined agitator and feeder D which comprises a plurality of radial arms 21 each of which has a depending flange 22 on the trailing edge thereof, said flanges being of such dimensions as to extend throughout the major portion of the inlet opening 14 and barely clear the horizontal top edge of the flange 15 as said arms 25 rotate across the inlet.

Vertically disposed scraper arm 23 is secured to the agitator D and extends upwardly in contact with the inner wall of the container to remove any grease that may tend to adhere to said wall.

30 With this construction, it will be observed that when the drive shaft 12 is driven, the gear pump will be operated so as to draw the grease from the container into the inlet opening 14 and force said substance through the pump outlet 13. At the same time, the arms 21 and 35 flanges 22 will draw the grease from the tank and force it against the flange 15 and into the inlet 14 with a mashing or agitating action on the grease.

The pump outlet 13 is connected by a pipe 24 to the cylinder 25 of the high pressure pump mechanism E, and 40 a discharge hose 26 is connected to said cylinder for conducting the dispensed grease or other substance to the desired point of use, for example to a machine bearing, the hose having suitable valved nozzle 27. A spring closed ball check valve 28 prevents backward flow of the grease from the hose.

Generally, the gear pump gears rotate at slow speed, for example 34.5 R. P. M. and force the grease from the tank to the cylinder 25 of the reciprocating pump E at relatively low pressure, for example around 100 lbs. The reciprocating pump E provides a higher pressure at the discharge nozzle and includes a tubular piston 29 reciprocable in the cylinder 25 and actuated on its pressure-producing structure by a cam 30 on the counter-drive shaft 9. The piston is operated in the other direction by a spring 31 which is interposed between a flange 32 on the cylinder and a flange 33 on the exterior of the piston. The piston includes a ram jet relief valve which is shown as comprising a ball 34 held on a seat 35 by a spring 36, one end of which abuts the ball 34 while the other end abuts the other end of the piston, which in the present instance is a cap 37 screwed onto the piston.

With this construction, when the pump is operating and the cam 30 is rotated, the piston 29 will be rapidly reciprocated so as to force the grease from the cylinder 25 through the check valve 28 to the delivery hose, at high pressure which may be determined by the strength of the spring 36. When the nozzle valve is closed or some other obstruction to the flow of the grease through the hose is encountered, the spring 36 will yield and permit the ball 34 to move away from its seat to allow the grease to flow into the piston and through openings 38 in the walls of

the piston into the tank A, thus to relieve the hose from the high pressure generated by the pump E.

It will be observed that the piston 29 projects from one end of the cylinder 25 so that the piston can be easily and quickly inserted into and removed from the cylinder, and that the removable cap 37 on the piston provides for easy and quick interchange of the springs 36. The whole construction of the pump E is simple and inexpensive and provides an efficient combination of the pump and the relief valve.

Another feature of the invention above pointed out is the provision for variations in the gear ratio of the gear pump, and as shown this is effected by making the pump casing body 3 easily and quickly removable from the remainder of the apparatus so that different casing sections can be interchanged. Figure 1 shows gears of one ratio while Figure 6 shows gears 39 and 40 of another ratio, but the centers of the gears and the corresponding openings for the shafts 16 and 9 in all of the casing bodies are spaced apart the same distance. Obviously, the pump chambers of the respective casing bodies will be different to correspond to the sizes of the respective gears.

As shown, the casing body 3 is set on the base portion 2 of the frame, and preferably positioning pins 41 are provided for holding the casing body against transverse movement. The casing body 3 and the casing cover 4 are separably secured together by any suitable means such as bolts 42. With this construction, the casing body 3 can be easily and quickly removed from the container and the casing cover can be easily removed from the casing body. Then, if desired, another casing body can be connected to the casing cover and set in the tank on the frame base portion 2.

While the invention has been described as embodied in certain structural details, it will be understood that this is primarily for the purpose of illustrating the principles of the invention and that the construction of the apparatus can be modified and changed within the spirit and scope of the invention.

What I claim is:

1. Apparatus of the character described comprising a container for a fluent substance to be dispensed under pressure, a gear pump having a casing removably mounted in said container and including a casing body with a pump chamber therein and a casing cover, two parallel rotatable shafts extending into said casing, one with its lower end projecting from the casing toward the bottom of said container and the other shaft having one end projecting from said casing toward the top of the con-

tainer, cooperating gears in said pump chamber each secured on one of said shafts and rotatable therewith, said pump having an outlet port and an inlet port opening into said container, means mounted on and rotatable with 5 said second shaft within the container for agitating said substance within the container above said pump inlet, and means for actuating the first-mentioned shaft, a reciprocating pump including a cylinder connected to said gear pump outlet and having a discharge passage, a hollow 10 piston reciprocable in said cylinder with one end projecting from the end of the cylinder opposite said discharge passage, a driving connection between said end of said piston and said lower end of the first-mentioned shaft for reciprocating said piston, said piston having a 15 valve opening and seat facing into said piston from said cylinder, a spring seated valve cooperative with said valve seat, there being a passage from said piston to the interior of said container at the side of said valve opposite said seat, said valve permitting flow of said substance 20 from said cylinder through the piston into said container upon creation of a predetermined pressure in said cylinder.

2. Apparatus of the character described comprising a container for a fluent substance, a reciprocating pump including a cylinder having a discharge passage, a hollow 25 piston reciprocable in said cylinder with one end projecting from the end of the cylinder opposite said discharge passage and into said container, means for supplying said substance to said cylinder, said piston having a valve opening and seat facing into said piston from said cylinder, a 30 spring seated valve cooperative with said valve seat, there being a passage from said piston to the interior of said container at the side of said valve opposite said seat, means for reciprocating said piston to pump substance from said cylinder through said discharge passage, said 35 valve permitting flow of said substance from said cylinder through the piston into said container upon creation of a predetermined pressure in said cylinder.
